UNITED STATES PATENT OFFICE.

JOHN J. MCGUIRL, OF MIDLAND, PENNSYLVANIA, ASSIGNOR OF ONE-HALF TO OLLIE P. VIGLE, OF YOUNGSTOWN, OHIO.

SELF-LUBRICATING DEVICE.

1,257,721.

Specification of Letters Patent. Patented Feb. 26, 1918.

Application filed September 20, 1916. Serial No. 121,108.

To all whom it may concern:

Be it known that I, JOHN J. MCGUIRL, a citizen of the United States, residing at Midland, in the county of Beaver and State of Pennsylvania, have invented certain new and useful Improvements in Self-Lubricating Devices, of which the following is a specification.

This invention relates to self lubricating devices, and has for its object to provide a device of such class, in a manner as herein-after set forth, for automatically lubricating a shaft or journal during the operation of the latter.

Further objects of the invention are to provide a self lubricating device which is comparatively simple in its construction and arrangement, strong, durable, efficient in its use, readily set up, automatic in its action, and inexpensive.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a side elevation of a self lubricating device in accordance with this invention showing the adaptation thereof in connection with an axle shaft and its bearing.

Fig. 2 is a top plan view of the device.

Fig. 3 is a section on line 3—3, Fig. 2

looking in the direction of the arrow.

Fig. 4 is a section on line 4—4, Fig. 2, looking in the direction of the arrow.

Referring to the drawings in detail 1 denotes a portable body having a support 5 depending therefrom and the said support 5 is flanged as at 7, 8. Extending through the flanges 7, 8, are securing devices 9, 9 for connecting the support 5 to the body 1.

The support 5, has its lower portion, centrally thereof, cut away to provide a chamber 10, the bottom of which is formed by a plate 12, connected against the support 5 by securing devices 11.

The reference character 2 denotes an axle

having a bearing 6 which is arranged against a seat 11, formed in the support 5. A track rail is indicated at 13 and upon which travels a wheel 3 carried by the axle 2. The hub of the wheel is indicated at 4.

60

Mounted upon the plate 12, within the chamber 10, is a receptacle 14, which provides a well 15 for lubricant. The receptacle 14 has flanges 16, through which extend securing devices 17, for fixedly securing the receptacle 4 upon the plate 12.

65

Positioned within the well 15, is a U-shaped member 17. The vertical arms of the member 17, are indicated at 18, 19, and each of said arms, near its upper end, is formed with a pair of slots 20. The slots of each pair of slots are spaced from each other. Positioned against the face of each of the vertical arms of the member 14, near the top thereof, is a shifting plate 21, and the said plates 21 bear against shafts 22, of a pair of feed rolls 23. Each of the rolls 23 has secured to each end a head piece 24 and formed integral with each of said head pieces is a shaft 22, the latter extending into the slot 20. The slots 20 are disposed vertically and are oval-shaped in contour and by such an arrangement the feed rolls 23 can be shifted vertically. Surrounding each roll 23 and extending between the head pieces 24 is a covering 25 which may be of leather, cloth, rubber, or other suitable material. By the arrangement set forth when the covering 25 becomes worn it can be removed and a new one substituted. The covering 25 can be roughened or knurled.

70

80

85

90

95

100

Each of the shifting plates 21, centrally of its lower edge is formed with an inwardly extending tongue 26 over-lapped by an end of a follower 27 and the latter at each of its ends is slotted to form a series of ears 28, 29 and 30. The tongue 26 of a plate 21, extends upon the ear 30 and is over-lapped by the ears 28, 29 and by such an arrangement the follower 27 is coupled to the plates 21 so that when the follower 27 is moved upward the plates 21 will be carried therewith and shift the feed rolls 23.

Fixedly secured to the follower 27, centrally of its lower face, by the fastening devices 31, is a pair of arcuate resilient members 32, which are connected together centrally by a clip 33, the latter having the fastening devices 31 extending therethrough. Interposed between the clip 33 and the bot-

105

110

tom of the member 17 is an expansion spring 34 which has its upper coil positioned between the members 32 and the follower 27 as at 35. The members 32 limit compression of the springs 34, as well as act in conjunction with the springs 34, to elevate the follower.

The function of the spring 34 is to force the feed rolls 23 upward and to maintain them in engagement with the shaft 2.

The said rolls 23 travel within the lubricant in the well 15 and as the shaft 2 revolves, the rolls 23 will also be revolved to automatically feed the lubricant to the shaft 2.

The operation of the said rolls 23 is due to the friction between the said rolls and the shafts and by such an arrangement it is obvious that the lubricating device is what 20 may be termed a friction operative device for the purpose of feeding lubricant to a shaft or journal.

What I claim is:—

1. A self lubricating device comprising a 25 pair of feed rolls adapted to engage and be operated by the element to be lubricated, a lubricant reservoir, a U-shaped member adapted to be arranged therein and having the shafts of the rolls extending therein, elevating plates engaging with said shafts for moving said rolls toward the element to be lubricated, a follower connected with said plates for vertically moving them, and means connected with the follower and abutting 30 against said member for shifting the latter.

2. A self lubricating device comprising a 40 pair of feed rolls adapted to engage and be operated by the element to be lubricated, a lubricant reservoir, a U-shaped member adapted to be arranged therein and having the shafts of the rolls extending therein, elevating plates engaging with said shafts for moving said rolls toward the element to be lubricated, a follower connected with 45 said plates for vertically moving them, means connected with the follower and abutting against said member for shifting the latter, and a removable cover for each of said rolls.

50 3. A self lubricating device comprising a pair of feed rolls adapted to travel in a body of lubricant and engaging and operated by

the element to be lubricated, a lubricant reservoir, plates abutting against the shafts of said rolls for shifting these latter to engage 55 said element for supplying lubricant thereto, a follower connected with said plates for vertically moving the same, and means for shifting the follower.

4. A self lubricating device comprising a 60 pair of feed rolls adapted to travel in a body of lubricant and engaging and operated by the element to be lubricated, a lubricant reservoir, plates abutting against the shafts of said rolls for shifting these latter to engage 65 said element for supplying lubricant thereto, a follower connected with said plates for vertically moving the same, resilient members arcuate in contour connected to and depending from the follower, and a 70 coiled spring having its upper end extending between the follower and said resilient members.

5. A self lubricating device comprising a 75 pair of feed rolls adapted to travel in a body of lubricant and engaging and operated by the element to be lubricated, a lubricant reservoir, plates abutting against the shafts of said rolls for shifting these latter to engage 80 said element for supplying lubricant thereto, a follower connected with said plates for vertically moving the same, resilient members arcuate in contour connected to and depending from the follower, and a coiled 85 spring having its upper end extending between the follower and said resilient members, and a removable covering for each of said rolls.

6. A lubricating device comprising a 90 lubricant feeding means adapted to travel in a body of lubricant, a lubricant reservoir, elevating plates for said feeding means, a follower connected to said elevating plates for shifting the same, resilient elements connected to and depending from said follower, 95 and a coiled spring having its upper coil interposed between said resilient members and said follower.

In testimony whereof I affix my signature in the presence of two witnesses.

JOHN J. MCGUIRL.
